Inventor:
Henri Grivel
for Attorney
J. G. Gruenwald

UNITED STATES PATENT OFFICE.

HENRI GRIVEL, OF GUEBWILLER, FRANCE.

GILL-INTERSECTING DOUBLE-NEEDLE COMB-DRAWING MACHINE.

Application filed December 27, 1922. Serial No. 609,247.

To all whom it may concern:

Be it known that I, HENRI GRIVEL, citizen of the French Republic, residing at Guebwiller, Department du Haut-Rhine, France, 5 have invented certain Improvements in Gill-Intersecting Double-Needle Comb-Drawing Machines, of which the following is a specification.

The present invention relates to improvements in gill intersecting needle comb drawing machines for wool, flax, hemp and similar materials, one of the said improvements more particularly consisting therein, that a plurality of needle-cylinders, with 10 interchangeable needle-number fittings and of which the relative position can be adjusted, are inserted before the needle combs, the object being on the one hand to obtain a more advantageous construction by reducing the needle-combs, and on the other hand to increase the production. Another feature of the improved machine according to the invention consists therein, that the upper needle comb-set is hinged about the driving 15 end of the worm device in such a way that the proper meshing of the screw-spindle and the relative position of the cams carried thereby remain unaltered, whereby after raising and securing the upper needle comb-set out of the way by means of a suitable 20 device provided for the purpose, fibrous material of any kind whatever may be drawn by means of a single needle comb-set: in such a case it is sufficient to adjust the 25 needle-cylinders which, as stated above, are according to the invention arranged so as to permit such adjustment. Adjustment is however also obtained through the drawing-cylinder, to the extent of about 1/25 of an 30 inch in height above the level of the needle combs of the lower set. This latter adjustment of the drawing-cylinder from the upper position for drawing with two needle comb-sets to the lower position for drawing 35 with a single needle comb-set is caused by an automatic tightening of the endless belt.

An embodiment of the improved drawing-machine according to the invention is, by way of example only, illustrated by the accompanying drawing, wherein:

Fig. 1 is a partial side-elevation showing two intermeshing rows of needle combs forming part of a so-called "gill intersecting drawing-machine."

Fig. 2 is a similar view, but with the upper needle-comb-set in the raised position.

As may be seen from the drawing, on the front worm-spindles *a* are mounted gear-wheels *b* having teeth with heads rounded as shown in the direction of their width, so 60 as to allow the upper needle comb-set *c*, of which the frame *d* is hinged or pivoted about the trunnion *e*, to be raised as shown by Fig. 2, without the position of the cams being altered thereby. These cams are 65 mounted in known manner on the screwing-spindles *a* and *f* in the case of a double row of needle combs or on one of said spindles in the case of a single row of needle combs. *g*, *h* and *i* indicate the needle-cylinders, of 70 which one *i* can be adjusted by means of the lever-arm *k* pivoted about the centre of *h*, and can be maintained in position by means of the lever-arm *l*. The needle-cylinders, of which the interchangeable needle-number 75 fittings vary from rough for *g* to medium for *h* and fine for *i*, constitute a preparation-machine which permits of the needle combs *m* being kept finer.

When it is desired to work with a single 80 needle comb-set, the upper needle combs *c* are raised. The amplitude of this movement is set by means of a suitable guide-member which in the embodiment illustrated consists of a curved arm *n* pivoted at *o* and 85 having a notch which, when the upper needle comb-set is raised, comes to bear on a projecting pin *p* of the frame *q* of the lower needle comb-set.

In the position Fig. 2 the needle combs *m* 90 can be taken out for cleaning purposes.

The adjustment of the drawing-cylinder *t* takes place through automatic tightening of the endless belt *z* by the pressure-hook *s* pivoted about the centre of *t*. For this 95 purpose, a pressure-lever *u* is pivotally connected to said pressure-hook as shown at *r*, and the said pressure-lever *u* on the one hand is subjected to the influence of a pressure-spring *v* and an adjustment-screw *w*, 100 and on the other hand exerts a pressure on a roller *y* mounted on the pulley-shaft *x* and thus causes the tightening of the belt *z*.

I claim:

1. In a drawing-machine of the kind set 105 forth comprising a frame and upper and lower intersecting needle comb-sets mounted therein, a plurality of cooperating needle-cylinders positioned before said needle comb-sets, and means for adjusting the position of said cylinders in relation to one another.

2. In a drawing machine of the kind set forth comprising upper and lower intersecting needle comb-sets mounted in a suitable frame, a drawing cylinder device arranged 15 to draw the material through said needle-combs and a belt and pulley-drive for said drawing-cylinder device, means for the automatic adjustment of such drawing-cylinder-device, comprising a C-shaped pressure-hook having its upper end pivoted about the spindle of the drawing-cylinder, a roller mounted on the spindle of the lower pulley a horizontal lever-member pivoted at 20 one end to the aforesaid pressure-hook, extending over and adapted to act upon said roller and adjustable means for exerting a resilient downward pressure on the other end of said lever-member.
- In testimony whereof I signed hereunto my name in the presence of two subscribing witnesses.

HENRI GRIVEL.
